MINE CAR SPRING BUMPER AND COUPLING

Herman H. Pancake, Huntington, W. Va., assignor
to American Car and Foundry Company, New
York, N. Y., a corporation of New Jersey

Application May 25, 1937, Serial No. 144,606

16 Claims. (Cl. 213—9)

This invention relates in general to spring bumpers and couplings for railway cars and particularly those used in mines and for other industrial purposes. Previous bumpers and couplings have been either of the solid type or of the spring type in which a common set of springs serve for absorbing both draft and buffing forces. When a common set of springs is used the draft forces are applied to the construction above the spring, therefore, causing a twist and binding of the parts. Also since the buff forces are so much larger than the draft forces, the springs must be designed to withstand the buffing action and are accordingly much too stiff for the draft forces. It is an object, therefore, of this invention to provide a spring bumper and coupling arrangement in which independent springs are provided for draft and buffing.

Another object of the invention is the provision of a spring bumper and coupling arrangement in which the springs will be arranged substantially in alignment with the forces which they are to absorb.

A further object of the invention is the provision of a spring bumper and coupling arrangement in which the draft and bumper members are entirely independent of each other and may be replaced in case of injury with a minimum expense.

These and other objects of the invention will be apparent to persons skilled in the art from a study of the following description and accompanying drawings, in which:

Figure 1 is a sectional view taken substantially on line 1—1 of Fig. 3;

Fig. 2 is a front end view of the arrangement shown in Fig. 1, and

Fig. 3 is a plan view of the combined bumper and coupler arrangement.

Referring now to the drawings in detail, it is seen that the bumper and coupling arrangement has been illustrated as applied to a mine car having sills of suitable formation which will be supported as is customary by the wheels and axles (not shown) of the car. The sills in the present instance are of bulk formation having an upper outwardly directed flange 2 to which the side floor portions 4 are attached and a vertical web portion 6 to which the central floor and end castings are attached. The central floor in the instance shown is provided with upwardly directed flanges 8 by which the floor is securely fastened to the sills and with an upwardly directed offset end flange 10 adapted to overlie and be secured to the rear horizontally extending portion 12 of the end casting now to be described.

The end member is preferably formed as a one piece casting having outwardly directed upper and lower horizontally spaced portions 14 and 16 respectively, which portions are joined by a sub-

stantially Z-shaped portion having an inner vertically extending flange 18 and an outer vertically extending flange 20 joined together by the substantially horizontal web 22. It is to be noted that the vertical flange 20 merges with the lower horizontal portion or flange 16 intermediate its ends, thus providing a rearwardly directed extension 24 adapted to be secured to and supported by the customary end belt or binder 26. The end member is formed on its top and sides with a laterally extending flange or rib 28 to which the end sheet 30 may be attached, it being obvious that in case of end dumping cars this flange would be eliminated. In order to suitably brace the Z portion and end construction a backing member 32 is provided which merges with an element of the Z at one end and with the horizontal floor supporting portion 12 previously referred to. This member includes an inclined portion 33, and said portion as well as the lower portions of the Z element are suitably braced by means of spaced gussets 34, thus forming an extremely strong end member. The edges of the horizontal portion 12, sloped portion 33 and of the Z element are joined to vertically extending end walls 36 adapted to receive suitable securing means, such as 38, by means of which the entire casting is secured to the webs of the side sills. The forward edge of the wall 36 outwardly of the Z element flange 20 is inclined inwardly as at 40 and as clearly shown in Figs. 2 and 3. The upper and lower flanges 14 and 16 also have their edges inclined in accordance with this wall 40, thus forming an outwardly directed opening of a width less than the distance between the side sills.

The outwardly directed opening of the end member is adapted to receive the bumper element 42 which is substantially of U-formation having upper inwardly directed flange 44 and lower inwardly directed flange 46 adapted to be supported on and movable with respect to the supporting flange 16 of the end casting. The vertical web of the bumper member is provided at suitably spaced points with spring seat elements 48 for positioning springs 50 at one end thereof, the other ends of said springs being suitably positioned by projections 52 formed on the Z element flange 20. The vertical web of this bumper cap is of sufficient height to permit the upper flange thereof to overlap and ride upon the lower flange 54 of an outwardly facing draft channel 55 having a vertical web 56 normally abutting the upper flange 18 of the Z element, while the upper flange 58 underlies the upper flange of the end casting. As can be seen, web 22 of the Z form member constitutes a support for draft channel 55 and further, the web 22, in cooperation with the upper flange 14, defines a pocket in which the draft channel 55 is received. The

vertical web 56 of the draft member is provided with spaced spring seats 60 with which springs 62 are engaged at one end portion thereof, the other ends of said springs being engaged by projections 64 formed upon a stop block 66. In order to retain the stop block in position vertical bolts 68 extend through the end flanges 14 and 16, thus rigidly holding the block relative to the car end member. As shown in Fig. 3, the bolts 10 68 extend through slots formed in the upper and lower flanges of the draft channel to permit outward movement of the channel, while the flanges of the bumper cap 42 are slotted to permit inward movement of the cap. It is also obvious that these 15 bolts 68 also serve the purpose of retaining the draft channel and bumper cap in their proper positions and that they limit the outer motion of the bumper cap under action of the springs 50. The customary coupling pin 70 is provided which 20 extends through slotted openings in the upper flange 14 of the end casting and the upper flange 44 of the bumper cap and also extends through holes 12 formed in the flanges of the draft channel, thus permitting the pin and draft channel 25 to move outwardly upon application of a draft force. Compression of the draft springs is limited by the length of the slots in the upper flanges of the end member and bumper cap, while compression of the bumper springs is limited by the 30 slots in the bumper flanges themselves.

It is obvious that since the bumper and draft elements are independent of each other, the relative proportions of each may be readily changed, that is, if desired the draft element may be made 35 very short and even and if desired the draft springs 62 may be combined into a single spring. It is also obvious that since the draft and bumper springs operate independent of each other, each 40 may be designed to withstand the forces imposed thereon and accordingly it is to be noted that in the instance shown the bumper springs are considerably heavier than the springs used to resist the draft forces.

While the device has been described more or 45 less in detail, it is obvious that various modifications other than those suggested will be apparent to persons skilled in the art and all such modifications are contemplated as fall within the scope of the following claims.

50 What is claimed is:

1. A mine or similar rail car having a floor, side 55 sills, and an end structure connecting the side sills, said end structure comprising vertically spaced upper and lower substantially horizontally 60 extending flanges, a Z form member connecting said flanges, said Z form member having horizontally spaced upper and lower flanges extending substantially vertically and constituting abutments for draft means and buffer means respectively, said buffer means being supported by the lower horizontal flange of said end structure, and a bracing means for the end structure secured to the floor at one end portion and inclined upwardly therefrom and connected to one of the vertically 65 extending flanges of the Z form member.

2. A mine or similar rail car having a floor, side sills, and an end structure connecting the side sills, said structure comprising upper and lower substantially horizontal flanges, a substantially 70 Z form member connecting said upper and lower flanges adjacent their rear edges, said Z form member having its web located substantially horizontal and constituting a support for a draft element, independent buffer means supported by said lower horizontal flange, a brace member for the

end structure secured to the floor at one end portion and inclined upwardly therefrom and joined to said end structure at its opposite end portion, and vertically arranged flanges joining the end portions of said horizontal flanges, Z form member and brace members together, and constituting attaching elements by which the end structure is secured to the side sills. 5

3. A mine or similar rail car having a floor, side sills, and an end structure connecting the 10 side sills, said structure comprising upper and lower substantially horizontal flanges, a Z form member joining said flanges, said member having its flanges extending substantially vertical with the connecting web positioned substantially horizontal, draft means and buffer means supported respectively by said web and said lower horizontal flange of the end structure, a brace member for the end structure secured to the floor at one end portion thereof and inclined upwardly therefrom and joined at its other end portion to said end structure, and vertically extending flanges joining the end portions of said horizontal flanges, Z form member and brace member and constituting attaching elements by which the end structure is secured to the side sills. 20

4. A mine or similar rail car having a floor, side sills, and an end structure connecting the side sills, said structure comprising upper and lower substantially horizontal flanges, a Z form 30 member having its web intermediate said flanges and substantially parallel thereto and its flanges extending substantially vertical to merge with said first mentioned flanges, draft means located between said upper flange and web and resting upon the latter, and independent buffer means supported upon said lower flange. 35

5. A mine or similar rail car having a floor, side sills, and an end structure connecting the side sills, said structure comprising upper and lower 40 substantially horizontal flanges, a Z form member having its web intermediate said flanges and substantially parallel thereto and its flanges extending substantially vertical to merge with said first mentioned flanges, draft means located between said upper flange and web and resting upon the latter, independent buffer means supported upon said lower flange, and securing means extending through said upper and lower flanges and through said draft and buffer means to prevent 45 excessive displacement thereof. 50

6. A mine or similar rail car having a floor, side sills, and an end structure connecting the side sills, said structure comprising upper and lower substantially horizontal flanges, a Z form 55 member having its web intermediate said flanges and substantially parallel thereto and its flanges extending substantially vertical to merge with said first mentioned flanges, draft means located between said upper flange and web and resting upon the latter, independent buffer means supported upon said lower flange, and bracing means merging with said Z form member to brace the same whereby said structure is strengthened to resist buffing and draft strains. 60

7. A mine or similar rail car having a floor, side sills, and an end structure connecting the side sills, said structure comprising upper and lower substantially horizontal flanges, a Z form member having its web intermediate said flanges 70 and substantially parallel thereto and its flanges extending substantially vertical to merge with said first mentioned flanges, movable draft means located between said upper flange and web, said draft means resting upon said web and normally 75

- abutting the upper flange of the Z member, independent buffer means movably supported upon said lower flange, and resilient means adapted to transfer the buffing strains to the lower flange of the Z member.
8. A mine or similar rail car having a floor, side sills, and an end structure connecting the side sills, said structure comprising upper and lower substantially horizontal flanges, a Z form member having its web intermediate said flanges and substantially parallel thereto and its flanges extending substantially vertical to merge with said first mentioned flanges, movable draft means located between said upper flange and web, said draft means resting upon said web and normally abutting the upper flange of the Z member, independent buffer means movably supported upon said lower flange, resilient means adapted to transfer the buffing strains to the lower flange of the Z member, and bracing means merging with said Z member behind said resilient means whereby said structure is braced against the buffing strains.
9. A mine or similar rail car having a floor, side sills, and an end structure connecting the side sills, said structure comprising upper and lower substantially horizontal flanges, a Z form member having its web intermediate said flanges and substantially parallel thereto and its flanges extending substantially vertical to merge with said first mentioned flanges, movable channel-shaped draft means located between said upper flange and web, said draft means resting upon said web and normally abutting the upper flange of the Z member, independent buffer means movably supported upon said lower flange, said buffer means overlapping a portion of the draft means and being movable relative thereto, resilient means opposing the movement of said draft and buffer means, and stops limiting the movement of said means.
10. A mine or similar rail car including a floor, side sills and an end structure connecting the side sills, said end structure comprising upper and lower substantially horizontal flanges, a Z form member having its web substantially horizontal and its flanges substantially vertical and joined with said upper and lower flanges, said upper vertical flange constituting an abutment, draft means engaging said abutment and supported by the web of the Z form member, and buffer means supported on the lower horizontal flange of the end structure.
11. A mine or similar rail car including a floor, side sills and an end structure connecting the side sills, said end structure comprising upper and lower substantially horizontal flanges, a Z form member having its web substantially horizontal and its flanges substantially vertical and joined with said upper and lower flanges, said upper vertical flange constituting an abutment, draft means engaging said abutment and supported by the web of the Z form member, and buffer means supported on the lower horizontal flange of the end structure and having its upper portion supported by said draft member.
12. A mine or similar rail car having a floor, side sills and an end structure connecting the side sills, said end structure comprising upper and lower substantially horizontal flanges, a Z form

member having its flanges substantially vertically arranged and joined with said upper and lower flanges and its web substantially horizontal, a draft member supported on said web and abutting the upper vertical flange of the Z form member, buffer means supported by the draft member and by the lower horizontal flange of the end structure, and resilient means in the draft element and in the buffer member for opposing the movements thereof.

13. A mine or similar rail car including a floor, side sills, and an end structure connecting the side sills, said end structure comprising vertically spaced upper and lower substantially horizontal flanges, a Z form member connecting said flanges and having horizontally spaced upper and lower flanges extending substantially vertical and constituting abutments for draft and buffer means respectively, said last named flanges being connected by a web arranged substantially parallel to said first named flanges and constituting a support for the draft means, said buffer means being supported by the lower horizontal flange of said end structure, and a backing member connected to the upper vertically extending flange of the Z form member adjacent the web thereof and inclined downwardly therefrom and secured at its lower end portion to the car floor.

14. As an article of manufacture for mine or similar rail cars, an end structure comprising upper and lower vertically spaced substantially horizontal flanges, a Z form member having horizontally spaced flanges extending substantially vertically and connected to the inner edges of said first named flanges and in turn being connected by the substantially horizontally extending web of the Z form member, said lower horizontal flange of the end structure being so arranged as to constitute a support for buffer means.

15. As an article of manufacture for mine or similar rail cars, an end structure comprising upper and lower vertically spaced substantially horizontal flanges, a Z form member having horizontally spaced flanges extending substantially vertically and connected to the inner edges of said first named flanges and in turn being connected by the substantially horizontally extending web of the Z form member, said lower horizontal flange of the end structure being so arranged as to constitute a support for buffer means, and a bracing means connected to one of said last named flanges and inclined rearwardly and downwardly therefrom substantially into the plane of the lower of said first named flanges.

16. In a mine or similar rail car comprising a floor and side sills, an end structure arranged between and connected to the side sills and comprising upper and lower substantially horizontal flanges, a Z form member connecting said flanges, said member having its spaced flanges substantially vertically arranged with the connecting web arranged substantially horizontally, draft means and buffer means supported respectively by the web of the Z form member and said lower horizontal flange of the end structure, and means connecting said end structure to the floor comprising a member inclined downwardly from the upper portion of the Z form member to said floor.
